(57) **CLAIM**

I claim the ornamental design for a bottle, as shown and described herein.

DESCRIPTION

FIG. 1 is a top, back and right side perspective view of the bottle;

FIG. 2 is a left side elevational view thereof;

FIG. 3 is a front elevational view thereof, the rear elevational view being a mirror image except for the unclaimed threads; and,

FIG. 4 is a top plan view thereof.

The broken line showing of the bottle pour spout and thread show environmental structure which forms no part of the claimed design.
